TUNING ARRANGEMENT

Clifford G. Fick, Schenectady, N. Y., assignor to
General Electric Company, a corporation of
New York

Application August 24, 1942, Serial No. 455,827

2 Claims. (Cl. 250—33)

1

My invention relates to tuning arrangements, and more particularly to means whereby radiating antenna systems may be tuned to a particular operating frequency.

It is frequently desired to operate radio transmitters over a wide range of frequencies with a single antenna. The impedance of any particular antenna varies over a wide range of impedances at various frequencies. Where a particular antenna is to be excited at a frequency such that it exhibits high reactance and high resistance, it is usual to connect the transmitter to the antenna through a reactance equal and opposite to that presented by the antenna at that frequency, so that the combination of reactance and antenna is series resonant. Such a series resonance combination is capable of developing the high voltage necessary to excite an antenna at a frequency at which it exhibits high reactance and high resistance.

At certain frequencies an antenna exhibits an inductive reactance which is so great that the extremely low value of capacity required for series resonance cannot be physically realized. Stray capacity from the antenna connection near the transmitter and from the capacity with which the antenna is to be made series resonant are sufficient in such cases to make the required condenser capacity less than zero. It is accordingly an object of my invention to provide new and improved means whereby an antenna system may be excited efficiently at a frequency where it exhibits such high inductive reactance.

It is a further object of my invention to provide means whereby the excitation of an antenna under such conditions may be accomplished with simple and easily adjusted tuning means.

The features of my invention which I believe to be novel are set forth with particularity in the appended claims. The invention itself, both as to its organization and manner of operation, together with further objects and advantages thereof may best be understood by reference to the following description taken in connection with the accompanying drawing in which Fig. 1 illustrates an antenna tuning circuit embodying my invention; Fig. 2 shows certain impedance characteristics of antennae of the type shown in Fig. 1; and Fig. 3 illustrates certain vectorial relations existing between the voltages and currents in the circuit depicted in Fig. 1.

In Fig. 1 an antenna 10, which is shown schematically, is supplied with high frequency power from a radio transmitter 11 through a tuning arrangement 12. The output of the transmitter 11 is impressed across an inductance 13, of which

2

one terminal is grounded, and which is arranged in adjustable inductive relation with a second inductance 14, of which one terminal is also grounded. The ungrounded terminal of inductance 14 is connected through an adjustable inductance 15 to a movable switch member 16 which cooperates with three stationary contacts 17, 18 and 19. Condensers 20, 21 and 22, of different sizes are connected respectively between fixed contacts 17, 18 and 19 and a terminal 23 to which the antenna system 10 is connected. An inductance 24 of very low resistance is connected between the terminal 23 and ground.

In Fig. 2 the reactance and resistance characteristics of antenna systems in general are illustrated, such characteristics being applicable to any form of the antenna 10. Curve 30 of Fig. 2 shows the variations in the reactance of an antenna with frequency. For this curve 30, the reactances are plotted as ordinates, inductive reactance being plotted in the positive upward direction, and capacitive reactance being plotted in the downward negative direction. Frequencies are plotted as abscissae, one unit of frequency being that lowest frequency at which an antenna is resonant. At very low frequencies an antenna is capacitively reactive, as indicated by the portion 31 of curve 30, and at somewhat higher frequencies it becomes inductively reactive, as indicated by the portion 32 of curve 30. At still higher frequencies, the antenna alternately becomes capacitively reactive and inductively reactive, passing through a point of zero reactance, or resonance, each time the sign of its reactance changes.

Curve 33 of Fig. 2 illustrates the variation of resistance of an antenna with changes in frequency. The major part of such resistance is radiation resistance, which is maximum at frequencies where the reactance of the antenna changes sign most abruptly.

According to my present invention, the radio transmitter 11 operates at frequencies at which the antenna 10 exhibits large inductive reactance, as at points along the portion 32 of the curve 30, or at similar portions of the curve 30 at higher frequencies. The inductance 24 has a reactance at the frequency of operation of the transmitter 11 which is small relative to the inductive reactance of the antenna 10.

In operation, coupling between the inductances 13 and 14 is reduced to avoid overloading of the transmitter 11 during tuning operation. Switch member 16 is operated to connect that one of the condensers 20, 21, 22 in circuit with the adjustable inductance 15 such that adjustment of the

inductance 15 may be made to tune the system between the transmitter 11 and the antenna 10 and inductance 24 to resonance. After such adjustment is attained, at which the inductance 15 and one of the condensers 20, 21, 22 have such values that the system is resonant as a whole, coupling between the inductances 13 and 14 is increased until a suitable load is imposed on the transmitter 11.

Of course, it should be understood that the tuning means 15 through 22 may be any suitable reactance element or combination of reactance elements suitable for tuning the parallel combination of antenna 10 and inductance 24. It may, for example, be a single variable condenser, or if greater range of frequency adjustment is desired, it may be a plurality of such condensers with suitable switching means.

The reactance of that one of the condensers 20, 21, 22 which is selected at the particular operating frequency of the transmitter 11 must be larger than the reactance of the inductance 15, so that the net reactance of inductance 15 and that one of the condensers 20, 21, 22 which is connected in circuit is capacitive. This capacitive reactance is adjustable by adjustment of the inductance 15 and serves to tune the entire system.

In Fig. 3 the vector E_{10} represents the voltage which appears between the antenna 10 and ground, that is, the voltage across the inductance 24. This voltage, as explained previously, must be extremely high in order to excite the antenna 10 at a frequency at which it exhibits extremely high impedance. This high voltage is attained by the tuning means 15 through 22. The current vector I_{24} represents the current flow through the inductance 24 when the voltage represented by the vector E_{10} exists across it. The vector I_{10} illustrates the current flowing into the antenna 10 when the voltage represented by the vector E_{10} exists between the antenna and ground. The vector I_{15-22} represents the vectorial resultant of the current vectors I_{10} and I_{24} , and represents the total current flowing through the tuning means 15 through 22.

Since the total current flowing through the tuning means 15 through 22, as represented by the vector I_{15-22} , is much larger than the current flowing through the antenna 10, represented by the vector I_{10} , the impedance of the parallel combination of inductance 24 and the antenna 10 is much smaller than the impedance of the antenna alone at the particular operating frequency represented by the vectors of Fig. 3. It should be noted that the vector I_{10} makes a much smaller angle with the vector E_{10} than does the vector I_{24} , because radiation resistance and the like of the antenna 10 produce a substantial apparent resistance in the antenna 10. It is desirable that current flow through the inductance 24 should be large, and that inductance should be of high quality, that is, its resistance should be very low, so that losses in the inductance are a minimum.

The vectorial diagram of Fig. 3 shows that the impedance of the antenna 10, represented in Fig. 3 by the relation between the vectors I_{10} and E_{10} , is much greater and is more nearly resistive than the impedance of the parallel combination of antenna 10 and inductance 24, represented by the vectors I_{15-22} and E_{10} . With the more reactive impedance of the parallel combination of antenna 10 and inductance 24, the tuning means 15 through 22 must appear as a much larger capacity, so that tuning is greatly simplified.

Viewed in another way, the inductance 24, placed in parallel to the exciting connections for the antenna 10, acts as a transformer, the inductive reactance of the combination appearing at the connection 23 as a much smaller reactance than if the inductance 24 were omitted from the circuit. Further, the tuning means 15 through 22, together with the inductance 24 in parallel with the antenna 10, have a transformer action such that the voltage in inductances 13 and 14 necessary to excite the antenna 10 is small and the current large, whereby the resistance of the antenna 10 appears smaller, when the inductance 24 is used in parallel to the connections to the antenna 10. Without the inductance 24, the radio frequency current would be vanishingly small and the voltage so high as to make the design of coupling inductances 13-14 difficult in view of the necessity of matching the output of the transmitter 11 to the high reactance and resistance exhibited by the antenna. Such design is especially difficult where the antenna is to be used over a wide frequency range, such that at times the antenna exhibits low reactance and resistance. By my present tuning arrangement including the inductance 24, I have simplified the design of the coupling inductances 13 and 14 by reducing the apparent impedance of the antenna 10, as measured through the tuning means 15 through 22, from the high values the antenna actually assumes at the particular frequencies in question. Of course, the inductance 24 is made no smaller than is necessary to decrease the apparent inductive reactance of the antenna 10 to a workable value such that the tuning means 15 through 22 can be made to tune the antenna properly and the coupling means 13, 14 to match the transmitter impedance to the tuning means and antenna. It is desirable to make the inductance no smaller than necessary in order to minimize inevitable losses in the inductance, which may be minimized by making the resistance of the inductance 24 as small as possible.

While I have illustrated my invention as being used with an antenna radiating radio frequency power, it should be understood that it may be employed with any load circuit into which high frequency energy is to be transferred, which load circuit exhibits high inductive reactance at the frequency of the high frequency energy.

While I have shown and described a particular embodiment of my invention, it will be obvious to those skilled in the art that changes and modifications may be made without departing from my invention in its broader aspects, and I, therefore, aim in the appended claims to cover all such changes and modifications as fall within the true spirit and scope of my invention.

What I claim as new and desire to secure by Letters Patent of the United States is:

1. In combination, a source of high frequency energy, a load circuit exhibiting high inductive reactance at the frequency of energy from said source, means for connecting said load and source and for tuning said load to the frequency of energy from said source, the inductive reactance of said load being so high as to require the capacity of said tuning means to be vanishingly small for resonance, and means comprising an inductance connected across said load for reducing the effective inductive reactance of said load as it appears in combination with said inductance to an inductive reactance sufficiently low that said tuning means is a physically realizable capacity.
2. In combination, a source of high frequency

energy, an antenna arranged to radiate such energy and exhibiting high inductive reactance at the frequency of energy from said source, an inductance connected between said antenna and ground having an inductive reactance at the frequency of energy from said source small relative to the reactance of said antenna, a capacitive reactance connected between said source and the point of connection of said antenna and said inductance, said capacitive reactance being of such value as to resonate the inductive reactance presented to said point by said antenna and said inductance at the frequency of said high frequency energy.
